DRILL PIPE PROTECTOR APPLICATOR

Adelbert M. Graham, Beverly Hills, Calif., assignor to Walter G. L. Smith, Los Angeles, Calif.

Application July 20, 1940, Serial No. 346,615

2 Claims. (Cl. 29—88.2)

My present invention relates to a device for applying expansible annular protectors to drill pipe or other members which are to be operated in a well.

The invention is of especial utility with drill pipe employed in the rotary system of well drilling wherein a string of drill pipe is employed as a means for rotating a drill at the bottom of the well for the purpose of increasing the depth thereof. Such drill pipe consists of lengths of steel pipe secured together by sleeve couplings and by tool joints. It is now a practice to place on the drill pipe at suitable intervals sleeve members of a rubber compound molded with their internal diameters smaller than the external diameter of the pipe so that the protectors must be stretched in order to be placed on the drill pipe, the result being that tension acting in the walls of the protectors will cause them to tightly grip the pipe. When applied to the pipe, the external diameters of these drill pipe protectors is larger than the diameter of the tool joints and couplings, with the result that during the operation of the drill pipe in the well the tool joints, collars, and couplings will not contact the side wall of the hole or a casing set in the hole. Accordingly, wear on the drill pipe or its coupling means and wear on the casing in which the drill pipe may be operated is substantially avoided.

It is an object of this invention to provide means for expanding an expansible drill pipe protector of rubbery material and placing the same in expanded condition on a member having a substantially cylindrical exterior surface, after which the protector is transferred from the member to a desired position on a drill pipe.

It is a further object of the invention to provide a means for holding a drill pipe protector or wear preventer in expanded condition and whereby the protector may be applied directly to the position on the drill pipe which it is intended to occupy, thereby avoiding the necessity of sliding the wear preventor on the drill pipe.

It is a further object of the invention to provide a device, for holding a drill pipe protector in expanded condition and in a position surrounding a selected portion of a drill pipe, with means for transferring the protector directly to the drill pipe substantially without axial movement of the protector relative to the drill pipe after contraction.

It is an object of the invention to provide in a means such as set forth in the preceding paragraph a hollow wall for supporting a protector

in a position surrounding a drill pipe, and substantially without axial movement relative to the drill pipe, with means for moving the hollow wall out of the protector so that it may contract around the drill pipe substantially without axial movement relative to the drill pipe.

It is a further object of the invention to provide a simple means for expanding a protector and placing the same on a member having a substantially cylindrical exterior surface. In the practice of the invention the member to which the expanding means applies the expanded protector may be a cylindrical wall from which the protector is transferred to the surface of the drill pipe, or it may be the end of the drill pipe, a coupling or collar on the end of the drill pipe, or other cylindrical member at the end of the drill pipe from which the protector is placed in its desired position on the drill pipe.

It is a further object of the invention to provide means for expanding a protector whereby the protector to be expanded is forced over an expanding cone and wherein the force applied to move the protector over the cone comprises a tubular body of expansible material. In the preferred practice of the invention, the protector to be applied to the holder or to the drill pipe is forced over the expanding cone by means of a second protector disposed at the rear end thereof.

It is an object of the invention to provide an expanding means for applying a protector to a member having a cylindrical outer surface, this expanding means having a guide for guiding a protector as it is being moved over the expanding cone and onto the receiving member.

A further object of the invention is to provide a device of the character set forth in the preceding paragraph having means for applying force in axial direction to move the protector over the expanding cone and having a guide means movable in axial direction from a retracted position to a guiding position relative to the protector as it moves over the expanding cone onto the receiving member.

A further object of the invention is to provide a device such as set forth in the preceding paragraph wherein the guide member is automatically moved into operative position prior to the application of force to move the protector over the expanding cone and onto the receiving member or holder.

A further object of the invention is to provide a device of the character above set forth having means for rendering the guide member inoperative when the device is employed to expand pro-

tectors of such increased thickness that they do not tend to turn over or roll up during the movement thereof over the expanding cone.

A further object of the invention is to provide a simple hydraulic device for applying protectors to pipe, this device having a hydraulic expanding means disposed in spaced relation to a support for a holder or transferring device which receives the expanded protector, this holder being removable to a position surrounding the pipe to which the protector is to be applied, and such holder embodying means for moving the cylindrical wall on which the expanded protector is supported, from its position within the protector, to permit the protector to contract around a drill pipe.

Further objects and advantages of the invention will be brought out in the following part of the specification.

Referring to the drawings which are for illustrative purposes only:

Fig. 1 is a vertical sectional view showing a preferred form of my drill pipe protector expanding means with a holder or transferring device in place to receive the expanded protector.

Fig. 2 is a cross-section taken substantially on the plane indicated by the line 2-2 of Fig. 1.

Fig. 3 is a fragmentary sectional view showing a drill pipe protector forced by a second protector over the expanding cone of the device.

Fig. 4 is a fragmentary sectional view similar to Fig. 3 showing the relative position of the parts when the protector is moved onto the support.

Fig. 5 is a fragmentary view showing a manner in which the protector is transferred from the holder onto the drill pipe.

Fig. 6 is a fragmentary sectional view showing the manner in which the expanding device is employed to expand a protector, the wall of which is quite thick relative to the length and, accordingly, may be expanded over the expanded cone without it rolling or turning over.

In Fig. 1 of the drawings I show an expanding device A for expanding a protector 10 and placing the same on a member 11 having a cylindrical outer surface, such member being shown as part of a holder or transferring device B which is supported above the base 12 of the expanding device A. The expanding device A comprises a cylinder 13 having three projecting lugs 14 whereby it may be supported upon and connected to the base 12 by means of vertical rods 15.

The cylinder has at its lower end a ring 16 which projects inward and carries packing 17 to engage the outer surface of a cylindrical wall 18 forming part of a major piston 19 which has at its upper end a flange 20 carrying packing members 21 and 22 arranged respectively to seal against downward and upward pressure. The major piston 19 has at its upper end a wall or head 23 which confronts the upper end wall or head 24 of the cylinder 13. A pressure chamber 25 is formed in between the heads 23 and 24 in which fluid pressure may operate to move the piston 19 downward. An annular pressure chamber 26 is formed between the cylinder 13 and the wall 18 of the major piston 19 in which fluid pressure will act against the flange 20 to move the major piston 19 upward in the cylinder 13 or to resist downward movement of the piston 19.

In coaxial relation to the piston 19 a pusher 27 projects downward from the head 23 of the cylinder 13, this pusher comprising a cylindrical member threaded at 28 into the head 23, and

having an enlargement 29 at its lower end preferably having a downwardly spaced recess 30 therein. A cylindrical wall 31 projects downward from the head 23 of the piston 19 in coaxial relation to the pusher 27 and of such larger diameter as to be spaced from the pusher 27. Packing means 32 is disposed in the lower end of the cylindrical wall 31 to engage the outer surface of a tube or cylindrical wall 33 forming part of a guide member 34 having at its lower end an outwardly flared wall 35. At the upper end of the cylindrical wall 33 of the guide member 34 there is an inwardly turned flange 36 carrying packing 37 for sealing engagement with the pusher member 27. The head 23 of the piston 19 has openings 38, through which fluid pressure may be transmitted from the chamber 25 to the upper face of the flange 36, to move the guide member 34 downward relative to the piston 19 to a position indicated by dotted lines 34'. A guide bar or tube 39 is threaded into the lower end of the pusher 27, and this guide member 39 receives thereon the protector 10 and another protector indicated by the numeral 10' which is to serve as a means for transmitting the pushing force from the enlargement 29 of the pusher member 27 to the protector 10, as will be herein-after described.

The wall 11 of the transferring device B is relatively thin and at its lower end has an outwardly projecting flange 40 carrying upwardly and downwardly faced packing members 41 and 42. A cylindrical wall 43 projects downward from the flange 40, this cylindrical wall 43 being preferably a continuation of the wall 11. A cylindrical member 44 surrounds the walls 11 and 43 and the flange 40, this member 44 including an upper cylindrical guard wall 45 having at the lower end thereof an inwardly projecting flange 46 with packing means 47 to engage the outer face of the wall 11. The flange 46 lies above the flange 40. The member 44 has a cylindrical wall 46' which engages the packing means 41 and 42 of the flange 40 and extends downward over the wall 43. At the lower end of the wall 46' a plate 47 is secured, this plate 47 having an opening through which the lower portion of the wall 43 projects and carrying packing means 48 to engage the outer surface of the cylindrical wall 43. The outer member 44 of the transferring device B has diametrically opposed handles 49, as shown in Fig. 5, whereby the device B may be manually engaged so as to be moved from its position of Fig. 1 to a position above a rotary table 50, Fig. 5, so that a portion of a drill pipe 51 may be lowered through the device B.

Within the cylindrical wall 46', forming a part of the outer member 44, a chamber 52 is formed between the flange 46 and the flange 40, and a chamber 53 is formed between the flange 40 and the inwardly projecting portion of the plate 47 at the lower end of the wall 46'. A metal body 54 projects outward from the upper portion of the wall 46' and therein a passage 55 is formed, communicating with the chamber 52. On the plate 47 there is a projection 56 having therein a passage 57 which communicates with the lower end of the chamber 53. A four-way valve 58 has the upper port 59 thereof connected to the outer end of the passage 55 of the body 54 by means of a flange fitting 60, and the diametrically opposed lower port 61 of the four-way valve 58 is connected through a pipe 62 with the passage 57. The four-way valve 58, in accordance with known construction thereof, has, in addition

to the ports 59 and 61, a pair of diametrically opposed inlet and outlet ports, not shown. As shown in Fig. 5, a fluid pressure line 63 and a discharge line 64 are connected to these remaining ports of the four-way valve 58, such lines 63 and 64 being preferably flexible conduit or hose. By suitable rotation of the plug 65 of the four-way valve 58, fluid pressure may be introduced into the chamber 52 or the chamber 53 while at the same time the discharge hose 64 will be connected either to the chamber 53 or the chamber 52. Accordingly, fluid pressure may be applied to the upper face of the flange 40 to move the walls 11 and 43 downward relative to the outer structure 44, or fluid pressure may be applied to the lower face of the flange 40 to move the walls 11 and 43 upward relative to the outer structure 44 of the transfer device B.

As shown in Fig. 1, pressure and discharge lines 66 and 67 are connected to opposing ports of a four-way valve 68 and the remaining ports of this four-way valve 68 are connected respectively through piping 69 with the chamber 25 at the upper end of the cylinder 13, and through piping 70 with the lower end of the pressure space 26. The piping 70 has therein a check valve 71 which will permit a flow of fluid through the piping 70 and into the pressure chamber 26 in the direction of the arrow 72. The check valve 71 is bypassed by a pressure relief valve 13 having its inlet 74 connected to the piping 70 between the check valve 71 and the pressure chamber 26, and having its outlet 75 connected by piping 76 to the piping 70 between the check valve 71 and the four-way valve 68. In the ordinary operation of the device, the relief valve 73 is set so as to hold a pressure of 100 pounds against the interior of the chamber 26.

As shown in Figs. 1 and 2, a ring 77 is slidably disposed upon the base 12, this ring 77 having an extending arm 78 which swings on the lower portion of the leftward vertical bar 15, and the ring 77 is provided with a projecting handle 79, whereby force may be applied to swing the ring in clockwise direction from the position in which it is shown in Fig. 2 to a position wherein the ring 77 will lie in projecting relation to the edge 80 of the base 12. The ring 77, as shown in Fig. 1, has an annular rib to project upward into the lower end of the wall 43, whereby the transferring device B will be properly positioned relative to the expanding device A when the ring 77 is moved onto the base 12 to the position thereof shown in Fig. 2. The expanding device A includes a conical member 81 which is placed at the upper end of the wall 11 of the device B. This expanding cone 81 has a downwardly projecting annular rib 82 to project into the upper end of the wall 11, thereby centralizing the cone 81 with relation to the wall 11. The upper end of the cone 81 is provided with an opening 83 through which the bar or tube 39 may downwardly slide during the operation of the device.

The operation of the device is preferably carried out in the following manner. With the transferring device B in place below the expanding device A, and with the expanding cone 81 positioned as shown, the four-way valve 68 is manipulated so as to introduce liquid under high pressure through the piping 69 into the chamber 25. The pressure of fluid in the chamber 25 will tend to force the piston 19 downward, but the downward movement of the piston 19 will be resisted by the reaction of liquid trapped in the

chamber 26. Accordingly, when the pressure is first applied to the chamber 25 it will be transmitted through the openings 38 and will force the guide member 34 downward from the position in which it is shown in full lines to its dotted line position 34' surrounding the members 10' and 10. As the pressure builds up in the chamber 25, the pressure in the chamber 26 will be brought to a value exceeding the pressure for which the relief valve 73 is set and the piston 19, with the pusher 27 and the guide 34, will be forced downward relative to the expanding cone 81. The lower end of the bar 39 will enter the opening 83 and the lower end of the protector 10 will come into engagement with the upper lip 90 of the cone 81, with the result that the cone will enter the lower portion of the opening through the protector 10, and at the same time the members 10 and 10' will be compressed in axial direction so as to expand the same into engagement with the guide member 34. The lower portion of the protector 10 will be advanced part way up the expanding wall of the cone 81 before the flared wall 35 of the guide member 34 approaches relatively close to the expanding cone 81. The flared wall 35 of the guide member 34 will then rest against the outer surface of the protector 10 as it is forced downward over the expanding cone 81, and will remain in this position while the pusher member 27 continues to force the members 10' and 10 downward through the positions thereof shown in Figs. 3 and 4.

In Fig. 3 the pusher member 27 has advanced downward to such position as to bring the lower end of the member 10' into engagement with the upper lip 90 of the cone 81. At this time the lower end 93 of the protector 10 will be passing onto the upper portion of the cylindrical wall 11. It will be noted at this time that the lower ends of the pusher 27 and the cylindrical wall 31 have moved downward below the upper end or flange 36 of the guide member 34. In Fig. 4, further downward movement of the pusher 27 will force the member 10' downward and outward through the flaring annular space, defined by the cone 81, and the wall 35, and this movement of the member 10' will force the protector 10 out from the space between the parts 81 and 35 onto the external surface of the cylindrical wall 11, as shown in Fig. 4. At this time the four-way valve 68 may be manipulated to release pressure from the chamber 25 and to apply pressure through the piping 70 and the check valve 71 to the pressure chamber 26 to return the piston 19 to the raised position thereof shown in Fig. 1. As soon as the pressure is released from the upper end of the guide member 34, it may move upward a sufficient distance to permit the member 10' to slide upward, in reverse direction from its position of Fig. 4, back to a position around the guide bar 39.

At the completion of the operation described in the foregoing, the supporting ring 77 may be swung outward so as to carry the transferring device B out of the lower portion of the expanding device A whereupon the expanding cone 81 may be removed from the upper end of the cylindrical wall 11, and the device B, by use of the handles 49 on the outer member 44 thereof, may be transferred to the rotary table 50, Fig. 5, after which the drill pipe may be lowered through the cylindrical walls 11 and 43. The device B may be then supported stationary in a raised position relative to upper surface of the rotary table 50, for example, by two workmen lifting on

the handles 49. Then the four-way valve 58 may be operated to direct liquid under pressure through the passage 55 into the upper chamber 52 to force the flange 48 downward. Downward movement of the flange 48 relative to the outer member 44 will carry the cylindrical wall 11 downward, with the result that the lower end of the protector 10 on the cylindrical wall 11 will be first brought into engagement with the upper face of the flange 48. Thereafter further downward movement of the protector 10 will be prevented and the downward movement of the inner element of the transferring device B will pull the cylindrical wall 11 downward out of the opening of the protector 10, permitting the same to contract around the adjacent portion of the drill pipe 51.

In the use of the expanding device A for protectors of the larger sizes, and for protectors having walls which are quite thick relative to the length thereof, I lock the guide member 34 and the member 27 together, as shown in Fig. 6, so that the guide member 34 cannot move downward relative to the thrust member 27. To lock these parts together, as described, I provide a cone plug 95 having a threaded projection 96 whereby it may be screwed into the lower end of the thrust member 27. This plug 95 has a flange or lip 97 to engage the upper inner portion of the flared wall 35 of the guide member 34, thereby preventing downward movement of the guide member 34 relative to the thrust member 27. An inner support or guide bar 98, analogous to the member 39 of Fig. 1, of required diameter for the size of the protector 100, is secured in a position projecting downward from the plug 95, the support 98 being of such length as to receive the protector 100 and another protector 100' to be used to force the protector 100 over the expanding cone. In conjunction therewith an expanding cone 81' is employed having an opening 83' of a size to receive the member 98.

This expanding cone 81' is supported at the upper end of a wall 11' analogous to the wall 11 of Figs. 1, 3, and 4.

A preferred embodiment of my invention illustrated in the drawings is especially adapted to installation of drill pipe protectors on an oil well drill stem, but I do not care to be so limited. It is to be understood that the structural elements are subject to change in size, shape, and manner of assembly as falls within the scope under pendant claims.

I claim as my invention:

1. A device for expanding a resilient drill pipe protector sleeve having an axial opening therein onto a cylindrical member having a diameter materially larger than the normal diameter of said protector sleeve, comprising an expanding cone forming an approach to said cylindrical member, a guide bar, means supporting said guide bar in axial alignment with said expanding cone to support a protector sleeve by passing through the axial opening therein, a pusher member concentric with said guide bar, an annular guide member surrounding said pusher member, means supporting said annular guide member in concentric relation to said guide bar and for movement toward and from said expanding cone, said annular guide member flaring outwardly at its end adjacent said expanding cone to approximately parallel the walls of said expanding cone, and means for forcing the flared end of said annular guide member against the outer surface of the protector sleeve and for moving said pusher member toward said expanding cone to force a protector sleeve on said guide bar over said expanding cone onto said cylindrical member while at the same time pressure is exerted on said sleeve by said flared end.

2. A device as described in claim 1 in which the expanding cone is provided with an opening at its apex through which said guide bar passes.

ADELBERT M. GRAHAM.
